UNITED STATES PATENT OFFICE

THOMAS D. HAMMOND, OF SYRACUSE, NEW YORK, ASSIGNOR OF ONE-HALF
TO ELLEN J. KELLER, OF SAME PLACE.

CARPET-FASTENER.

SPECIFICATION forming part of Letters Patent No. 399,038, dated March 5, 1889.

Application filed June 7, 1888. Serial No. 276,342. (No model.)

To all whom it may concern:

Be it known that I, THOMAS D. HAMMOND, of Syracuse, in the county of Onondaga, in the State of New York, have invented new and useful Improvements in Carpet-Fasteners, of which the following, taken in connection with the accompanying drawings, is a full, clear, and exact description.

This invention consists, essentially, of jaws secured to the floor and adapted to receive and grip between them the edge of the carpet, and levers connected to the said jaws to close the same, as hereinafter fully described, and specifically set forth in the claim.

In the annexed drawings, Figure 1 is a detached side view of my improved carpet-fastener with its jaws in an open position. Fig. 2 is a side view of the same secured to the floor and in position to hold the carpet. Fig. 3 is a top plan view of the same, and Fig. 4 is a plan view of the blank from which the carpet-fastener is formed.

Similar letters of reference indicate corresponding parts.

c and *d* represent, respectively, the stationary jaw and the movable or spring jaw designed to grip the edge of the carpet, as represented by dotted lines in Fig. 2 of the drawings. The jaw *c* is sustained in its position by a base-plate, *a*, which is perforated, as shown at *e e*, for the reception of tacks or screws by which to fasten it to the floor, said base being formed at the end adjacent to the base-board *C* of the room with a post, *b*, which terminates in the rearward and downward projecting jaw *c*. Over the base *a*, and parallel therewith, lies the jaw *d*, preferably of the form of a spring-plate secured at its heel to the aforesaid base, and having its opposite end free and extending under the jaw *c*, so as to allow it to close therewith. Under the spring-jaw *d* is a suitable tightener, *o*, preferably of the form of a cam formed on the end of a lever, *l*, which is pivoted to the post *b*. By turning said lever from a vertical to a horizontal position the cam *o* is caused to pry up the jaw *d* and crowd the same toward the

stationary jaw *c*, and thus grip the edge of the carpet inserted between the two jaws. The gripping end of the jaw *d* is to be serrated or provided with teeth *t t*, to allow it to obtain a firm hold on the carpet.

The aforesaid base-plate *a*, post *b*, and jaws *c* and *d*, I prefer to form from a single blank, *B*, stamped out of sheet metal by means of a suitable die, said blank consisting of an elongated strip perforated at *e e* for the reception of the attaching tacks or screws and at *e'* to serve as a pivot for the lever *l*, and serrated at the opposite end, as illustrated in Fig. 4 of the drawings. By folding the blank on the dotted line *l* back upon itself the jaw *d* is formed over the base *a*, and by bending the blank at proper angles on the dotted lines 2, 3, and 4 the post *b* and jaw *c* are formed. In this manner I obtain a simple, convenient, and very effective carpet-fastener. By securing the requisite number of such carpet-fasteners to the floor near the base-board and distributing them proper distances apart a carpet properly connected to said fasteners is held perfectly taut and smooth.

Having described my invention, what I claim as new, and desire to secure by Letters Patent, is—

The within-described carpet-fastener, composed of the base *a*, post *b* at one end of said base and terminating in the rearward and downward projecting jaw *c*, the spring-plate *d*, placed over the base *a*, parallel therewith, and having its heel secured to said base and its opposite and free end under the jaw *c*, and the lever *l*, pivoted to the post *b*, and provided with the cam *o* under the free end of the plate *d*, substantially as described and shown.

In testimony whereof I have hereunto signed my name, in the presence of two witnesses, at Syracuse, in the county of Onondaga, in the State of New York, this 5th day of June, 1888.

THOMAS D. HAMMOND. [L. S.]
